UNITED STATES PATENT OFFICE.

JAMES W. OGLE, OF MADISON, ILLINOIS.

BORING-MACHINE.

973,136.

Specification of Letters Patent. Patented Oct. 18, 1910.

Application filed March 5, 1909. Serial No. 481,283.

To all whom it may concern:

Be it known that I, JAMES W. OGLE, a citizen of the United States, residing at Madison, in the county of Madison and State of Illinois, have invented a new and useful Improvement in Boring-Machines, of which the following is a specification.

This invention relates to a device for boring holes in car sills after the floor has been laid, and also for boring holes in parts of cars where a limited amount of working room is available.

The device can be made in various sizes, and in the accompanying drawings the device has been exaggerated in size to more clearly bring out the details of construction.

The invention consists of a frame provided with a drilling shaft, a drive shaft at right angles to the drill shaft, and an adjustable gage carried by the frame and drive shaft.

The invention also consists in the novel features of construction hereinafter set forth, pointed out in the claims and shown in the accompanying drawings, in which:

Figure 1 is a side elevation showing the device in operation. Fig. 2 is an end view of the device looking toward the gage. Fig. 3 is a top plan view. Fig. 4 is a detail sectional view illustrating the manner of locking the drill to the drill shaft.

In these drawings 1 represents a suitable frame formed of flat metal bars and provided adjacent an open end with a cross bar 2. A drive shaft 3 is loosely journaled in the cross bar and in the opposite end of the frame 1 and carries at its inner end a beveled gear 4, the hub 5 of which rests upon the cross bar 2. A hollow drill shaft 6 is journaled in the sides of the open end of the frame and has fixed upon the outer end of the shaft 6 and a set screw works through said sleeve and through the shaft and locks in its adjusted position a drill rod 10, and by adjusting the said rod in the sleeve 8, the length of the hole to be drilled can be gauged.

To adjust the device to drill into a sill a pre-determined distance beneath the car floor a gage is provided which consists of a bar 11, the body portion of which is parallel to a side of the frame 1, and which is pro-

vided with an angled end portion 11^a through which the drive shaft 3 loosely passes. A bracket 12 carried by the frame 1 is provided with a threaded pin 13 which extends through a longitudinal slot 14 formed in the gage 11, and the gage is locked in its adjusted position by a wing nut 15. A roller 16 is mounted in the free bifurcated end of the gage 11 and travels upon the under side of the car floor as the drill enters the sill. A suitable scale is laid off upon the gage 11 adjacent the slot 14 and by adjusting the gage so as to move the scale relative to the pin 13 and then tighten the nut 15, the device may be adjusted so that when the roller engages the under side of the car floor, the drill will enter the sill in a horizontal line at a pre-determined point.

What I claim is:

1. A device of the kind described comprising a frame, drill holding means arranged adjacent one end of the frame and transverse thereto, an operating shaft journaled longitudinally in the frame and being provided with a crank portion adjacent the end of the frame opposite the drill holding means, means for transmitting rotary motion of the said shaft to the drill holding means, a gage consisting of an angled bar arranged parallel to and outside of the frame, one end of said bar being loosely mounted upon the said shaft, the other end projecting beyond and at right angles to the drill holding means, and means carried by the frame for supporting the last mentioned end portion of said gage.

2. A device of the kind described comprising a frame, drilling mechanism carried thereby, a drill working at right angles to the frame, a bar parallel to and extending beyond the ends of the frame, said bar being slotted adjacent one end and angled adjacent the other end, the angled portion working loosely upon a shaft of the drilling mechanism, a roller carried by the slotted end, a pin carried by the frame and extending into the slot, and a wing nut working upon said pin, as and for the purpose set forth.

3. A device of the kind described comprising a frame, a drill shaft carried transversely by the frame, a drive shaft carried by the frame at right angles to the drill

shaft, intermeshing gears carried by said shafts, a gage arranged parallel to the frame, one end of the gage being slotted, and the other end being angled, a drive shaft passing loosely through the angled portion, a roller carried by the slotted end portion, a pin carried by the frame and ex-

tending through the slot, and a nut working upon said pin and clamping the gage against movement relative to the frame.
